UNITED STATES PATENT OFFICE.

BENJAMIN P. SAUNDERS, OF IATAN, MISSOURI.

SHIPPING-CAN.

1,155,447.

Specification of Letters Patent.

Patented Oct. 5, 1915.

Application filed February 9, 1914, Serial No. 817,508. Renewed August 20, 1915. Serial No. 46,528.

To all whom it may concern:

Be it known that I, BENJAMIN P. SAUNDERS, a citizen of the United States, residing at Iatan, in the county of Platte and State 5 of Missouri, have invented certain new and useful Improvements in Shipping-Cans, of which the following is a specification.

My invention relates to improvements in shipping-cans, and my object is to produce 10 a can or container of this character, whereby butter, lard, and other fat-containing products may be safely shipped by parcel post.

The container is air-tight, so that its contents cannot become contaminated when placed in juxtaposition with other products, neither can said contents escape from the container and grease or injure other merchandise.

20 The invention is simple in construction and inexpensive to manufacture, and in order that said invention may be fully understood, reference will now be made to the accompanying drawing, in which:

25 Figure 1 is a vertical central section of the container. Fig. 2 is a plan view of the container with the lid open and partly broken away. Fig. 3 is a broken front elevation of the container, and a latch for securing the lid thereof in closed position. 30 Fig. 4 is a content remover.

In carrying out the invention, I employ a container 1, made, preferably, of tin or other sheet metal and consisting of a cylinder 2 35 and a bottom portion 3.

The upper edge of cylinder 2 is bent outwardly to form a broad bearing surface 4 for a gasket 5, and then bent downwardly and inwardly against the side of the cylinder to brace and support the bearing surface 4.

40 6 designates a lid secured by a hinge 7 to the downwardly and inwardly bent portion 8 at the upper end of the cylinder.

45 Lid 6 is provided at a point diametrically opposite hinge 7 with a depending lip 9, having an inwardly extending lug 10 for engagement with an eccentric latch 11, pivotally secured to the adjacent side of cylinder 2 by a pivot 12. Latch 11 has a handle 13, whereby it may be rocked on its pivot 12 to engage or disengage the stud 10. By

having the eccentric portion 14 of the latch engage the stud 10 as shown on Fig. 3, said latch firmly draws the lid 6 down upon the 55 gasket 5, thereby making the upper end of the container 1 air-tight.

The container remover shown in Figs. 1 and 4, comprises a plate 15, a rod 16, and a finger ring 17. Plate 15 fits snugly within 60 the container but is free to be withdrawn therefrom, and has a raised central portion 8 with a central threaded aperture to receive the threaded lower end of the rod 16, which is further secured by a wing-nut 19. 65

In practice, the butter or other produce to be shipped is, preferably, molded to fit snugly within the container 1, but before inserting it therein the rod 16 is pushed through the central portion of the molded 70 produce, then screwed into the plate 15 and then reliably secured by the wing-nut 19. The produce resting upon the plate 15, is now inserted in the container 1, which is sealed by drawing the lid 6 firmly against 75 the gasket 5 through the intermediary of the latch 11. On reaching its destination the produce can be readily removed from the container on opening the lid 6, inserting the finger through the ring 17, and withdraw- 80 ing the content-remover, which is taken from the produce after unscrewing rod 16 from the plate 15.

The container may be made in different sizes to hold one or more pounds of produce, 85 and it can be made in any cross sectional form, so that the least space is occupied when shipping a number of containers together.

Having thus described my invention, what 90 I claim and desire to secure by Letters Patent is:

In a receptacle of the class described, a container having a closed bottom, a plate removably mounted in the container, said 95 plate having an upwardly extending pocket formed centrally thereof, and having its open end confronting the bottom of the container, a rod having a threaded end, said pocket having a threaded aperture therein 100 for engagement by the threaded end of the rod, a lock nut confined in the pocket and above the bottom of the container, said nut being removably engaged with the threaded

end of the rod, said rod being adapted to penetrate centrally material in bulk previous to the placing of the material and plate in the container, said rod and plate being removable from the container with the material, and a ring connected to the upper end of the rod and being pivotally connected thereto, whereby said ring can lie in a horizontal position on the top of the material

and below the plane of the upper edge of the container.

In testimony whereof I affix my signature, in the presence of two witnesses.

BENJAMIN P. SAUNDERS.
